DEVEREUX LORD, OF BROOKLYN, NEW YORK

ATTACHMENT FOR TELEPHONES

Application filed January 21, 1929. Serial No. 333,768.

This invention relates to attachments for telephones and has for an object to provide a new, simple, efficient, and inexpensive attachment for the transmitter of a telephone which will permit the transmitter and receiver to be held by the user in one hand.

In the use of telephones made up of separate transmitting and receiving instruments which when not in use are connected by means of a hook member attached to the transmitting instrument upon which the receiver hangs, some disadvantage has been experienced in that often times the user has no convenient support for the phone and desires to make use of one hand for purposes other than holding the phone. Also with the regular telephone the user except when handling the phone with both hands is forced to place himself in position to use the telephone which may be upon some support and at times this position may be inconvenient or not as convenient as desired.

The present invention overcomes these difficulties by providing an attachment which may be secured directly to the transmitter, such attachment including a handle by which the user may hold the receiver in one hand and the handle in the same thereby leaving his other hand free for taking notes, etc. The attachment which includes the handle is so designed and constructed as to permit the handle part to fold against the upright part of the transmitter when not in use.

Other features and objects of the invention will become apparent by reference to the following detailed description of the accompanying drawings forming a part of the same, wherein

Fig. 1 is a perspective view of a telephone having the attachment of the invention secured thereto;

Fig. 2 is a perspective view of the same telephone when in use;

Fig. 3 is a perspective view of the attachment proper; and

Fig. 4 is a section taken on substantially the lines 4—4 of Fig. 3.

Referring now to the drawings, 10 indicates a telephone transmitter of a type in

common use which includes the usual mouth-piece 11 and receiver hook 12, which hook serves as a contact member for the receiving instrument proper 13, all of which is well known to the art.

Since in the use of a device of this character in instances where there is no convenient support for the transmitter 10 it becomes necessary to hold the transmitter 10 in one hand and the receiver 13 in the other, the disadvantage of this is apparent in that the user is not at liberty to take notes, etc., while using the instrument. To overcome this difficulty the present invention which comprises an attachment 14 may be utilized in connection with the transmitter 10. The attachment 14 consists of a band of material 15 preferably of some metallic substance, which band is so constructed that the ends 16 thereof may be forced apart or pulled together for attachment around the vertical cylindrical part of the transmitter 10. The band 15 may be secured to the transmitter by means of a bolt 17 and a nut 17^a which may be a wing-nut or one of any other desired type.

Secured to the band 15 is a substantially U-shaped member 18 provided with openings through which a pin 19 is adapted to pass. This pin 19 serves as a pivotal connection between the U-shaped member 18 and an elongated handle member 20 provided at its extremity with a ball 21. As shown clearly in Fig. 4 the extremity of the handle rod 20 remote from the ball 21, is provided with a shoulder 22 which in certain positions engages against the base of the U-shaped member 18.

The installation and operation of the attachment 14 in connection with the telephone transmitter is substantially as follows: The band 15 is clamped around the upright portion of the transmitter 10 by means of the bolt 17 and nut 17^a. As shown in Figs. 1 and 2 the bolt 17 is directly beneath the hooked contact member 12. If so desired, however, the band may be attached to the transmitter 10 in such a manner that the bolt 17 is above the hook 12 but spaced thereabove an amount suffi-

cient to prevent the same from interfering with the usual movement of the hook 12 in performing its designed purposes. In this position when in use the handle rod 20 with its accompanying ball 21 may be grasped by the user with the same hand which holds the receiver 13 leaving his other hand free to write, etc. When in use the shoulder 22 prevents the handle from being elevated to a greater height than a plane substantially perpendicular to the plane of the upright member. This shoulder, however, does not prevent the handle rod 20 from dropping to a position substantially parallel to the upright part of the transmitter when the same is not in use. The different positions of the handle portion are clearly illustrated in Figs. 1 and 2; Fig. 1 showing the handle not in use and Fig. 2 showing the same in use.

It will be apparent that the handle 20 may be connected to the band 15 at any desired point about the circumference of the same by means of the U-shaped member 18 but the preferred point of connection is shown in close proximity to the terminals 16 of the band 15 which position places the mouthpiece 11 in substantially correct position for speaking when the handle 20 and receiver 13 are held in the left hand of the user.

The present invention is capable of many modifications and it is to be understood that the same is not to be limited to the illustrated embodiments but is to be limited only by the scope of the following claims.

I claim:

1. An attachment for a telephone comprising a handle, means for securing the handle to the transmitting instrument, such handle being so constructed as to automatically fall into a line substantially parallel with that part of the instrument to which it is attached when not in use.
2. An attachment for a telephone transmitting instrument comprising a handle, means for pivotally securing the handle to said instrument, a stop for limiting pivotal movement of the handle, said handle being automatically returned to position against said instrument when not in use.
3. An attachment for a telephone transmitting instrument comprising a band adapted to be secured to said instrument, a handle pivotally connected to said band to lie adjacent to said instrument when not in use, and a shoulder on one end of the handle for limiting its upward movement.
4. An attachment for a telephone transmitting instrument comprising a handle hingedly connected to the upright portion thereof, and a stop for limiting pivotal movement of said handle away from said upright portion.
5. An attachment for a telephone trans-

mitting instrument comprising a band, means for removably securing the band to said instrument, a handle pivotally connected to said band to lie adjacent to the upright portion of the instrument when not in use, and a stop for limiting pivotal movement of said handle away from said upright portion.

In testimony whereof, I have signed my name to this specification.

DEVEREUX LORD.
